TRUNDLE TOY

Ernest L. Thornell, East Aurora, N.Y., assignor to Fisher-
Price Toys, Inc., East Aurora, N.Y., a corporation of
New York

Filed Mar. 6, 1967, Ser. No. 6,061

Term of patent 14 years

(Cl. D34—15)

FIG. 2

FIG. 1

FIG. 3

FIG. 4

FIG. 5

FIG. 6

FIG. 1 is a front perspective view of a trundle toy showing my new design with a pull cord omitted;

FIG. 2 is a rear perspective view of FIG. 1;

FIG. 3 is a bottom plan view thereof;

FIG. 4 is a front perspective view of a modified form of the design shown in FIG. 1 with the free end of the pull cord bearing a simulated key inserted in an aperture on one side of the roof;

FIG. 5 is a rear perspective view of the modified design shown in FIG. 4 with block receiving apertures on the roof;

FIG. 6 is a top perspective view of the modified design with a portion of the roof of the toy in a raised position.

I claim:

The ornamental design for a trundle toy, substantially as shown and described.
